UNITED STATES PATENT OFFICE.

EDWARD H. CHAPPUIS, OF MARYSVILLE, CALIFORNIA.

CYCLE SEAT AND HANDLE-BAR FASTENING ATTACHMENT.

SPECIFICATION forming part of Letters Patent No. 625,020, dated May 16, 1899.

Application filed December 13, 1897. Serial No. 661,727. (No model.)

To all whom it may concern:

Be it known that I, EDWARD H. CHAPPUIS, a citizen of the United States, residing at Marysville, county of Yuba, State of California, have invented an Improvement in Cycle Seat and Handle-Bar Fastening Attachments; and I hereby declare the following to be a full, clear, and exact description of the same.

10 My invention relates to a means for securing the saddle, saddle-post, handle-bar steering-posts, and handle-bars of cycles by the employment of cam locking devices having means by which they are directly operated without the use of screw-threaded bolts and nuts or wrenches; and it consists in the hereinafter described and claimed devices and attachments for said parts, whereby the fastening or releasing and adjustment of any of 15 the parts may be effected at once and without the application of any separate implement.

Referring to the accompanying drawings, Figure 1 is a side elevation of the seat-post and attachments. Fig. 2 is a rear view of the same, the saddle-clamp being in section on line $x x$, Fig. 1. Fig. 3 is a detail of the locking-block in the seat-clamp. Fig. 4 is a horizontal section on line $y y$, Fig. 2. Fig. 5 is a longitudinal section of the steering-post on line $w w$, Fig. 6. Fig. 6 is a horizontal section of the same on line $z z$, Fig. 5. Fig. 7 is a detail showing a portion of the seat-post and socket with portions broken away to show the 35 cam lever and block.

In the adjustment and securing of saddle-posts and handle-bar steering-posts to obtain the proper height for various riders and in the adjusting and securing of the seats and the 40 handle-bars for similar purposes, it has been customary to employ screw bolts and nuts, whereby the parts are clamped in place; but these devices are unsatisfactory and annoying, because, first, the amount of compression necessary to hold the parts in place is so 45 considerable that threads are often stripped from the bolts and the angles of the nuts are twisted and torn away, besides which it is not easy to maintain the parts in proper line and 50 prevent their being twisted out of place, whereby severe accidents may occur. My invention is designed to overcome this difficulty

by the application of a series of clamping devices for holding these parts in place.

In the present illustrations I have shown 55 the tubular seat-post socket A, having the seat-post B slidable within it, and the steering-post tubular socket C, having the handle-bar post D correspondingly slidable within it, both being adapted to be adjusted up and 60 down to suit the convenience of the rider. Upon the top of the seat-post is the seat bar or support E, and to this the saddle is adjustably secured by a clamp, and other clamps lock the saddle-springs F to this support at 65 any desired point, as will be hereinafter more fully described. The handle-bar is turnable in suitable holders in the upper end of the post D, so that it may be adjusted to suit the rider, and its post may also be raised or lowered in the socket similarly to the seat-post. 70 All these adjusting devices are actuated by cams which immediately lock and hold the parts to any point of adjustment.

The seat-post socket A and the handle-bar 75 socket C are provided with lugs a, projecting, as here shown, rearwardly, and between these lugs are fulcrumed the cam-levers G. The corresponding portions of the posts are transversely corrugated, so that when the post is 80 raised or depressed these corrugations are in line with the slotted openings in which the cam-levers operate. These levers have blocks H pivoted to them, and these blocks have their 85 faces which are adjacent to the posts correspondingly corrugated, so that when the cam is moved to lock the blocks against the seat-posts the two will be held firmly and prevented from sliding upon each other.

Upon each side of the corrugations in the 90 seat-post or handle-bar post are open channels, (shown at I,) and the cam-blocks H have flanges or projections J upon each side, which enter these slots or channels whenever the blocks are clamped against the posts. These 95 guides and channels serve to lock the parts accurately in line, so that there will be no mistake when the adjustment is made of twisting either seat-post or handle-bar to one side or the other, and they serve, additionally, to prevent the post from being twisted out of line by accident, thus relieving the 100 rider of the danger of serious accident from such a cause.

Upon the top of the seat-post B is the seat-bar or support E. The seat-post has a head formed upon its upper end, and this head is split or channeled downward and adapted to receive the flattened correspondingly-shaped portion of the support E.

The inner faces of the two sides of the head B' of the seat-post are formed with radial corrugations, and the flattened portion of the support E, which lies within the seat-post head, is correspondingly corrugated, so that when the two sides are clamped together upon this seat-support it will be held in the same manner, as previously described, in a straight line and prevented from turning.

K is a bolt passing centrally through the seat-post head and the corrugated portion of the seat-support, and it has a washer K' and a thumb-nut K² upon one end. Upon the other end is fulcrumed the cam-lever G', which operates when turned to either compress the sides of the seat-post head and clamp them firmly upon the seat-support or by turning in the opposite direction to release and allow the sides of the seat-post head to separate, so as to free the seat-support. When the pin K has been put into place, it is adjusted by means of the thumb-nut K² until it is in the proper relative position to allow the cam-lever G' to operate. After that adjustment has been made no change in this part will be necessary, the operation of securing and releasing being effected by means of the cam-lever, as before described. In order to prevent this cam-lever from turning, the shaft is flattened where it enters the seat-post head, fitting into correspondingly-shaped openings, which will insure the cam-lever remaining in its proper line of movement under all conditions.

The seat support or bar (marked E) is of sufficient length to allow the saddle to be moved forward or back upon it, and thus adjusted to suit the different peculiarities of riders. It is movable from end to end without being removed from the bar. The upper surface of this bar is transversely corrugated, as previously described, for the other locking-surfaces, and it is adapted to be engaged by a cam-block M, which fits into a channel in the top of a saddle-support N. Just beneath the upper corrugated surface and parallel therewith grooves or channels O are made longitudinally upon each side of the support E, and the lower part of the saddle-support N has inwardly-turned flanges, which fit and are slidable in these grooves. Upon each side of the part N are projecting lugs having holes made through them to receive the saddle-spring rods F, which may be adjusted therein and afterward locked by the cam-levers Q, fulcrumed on the part N and adapted to engage the rods F, as shown by dotted lines in Fig. 2. Within the channel in the upper part of N is fulcrumed a cam-lever G² of the same character as those previously described. This lever is connected with the movable cam-block M, so that when

turned in one direction it will raise and release it from the corrugations upon the top of E. The block has similar corrugations, so that when the parts have been moved forward or back to the proper adjustment the cam can be again pressed down, thus engaging and locking the block M with the corrugations of the part E and holding it securely, so that it cannot move in either direction. The guide-channels O and the corresponding engaging parts of N insure the saddle always remaining in a proper position transversely and preventing it from being tilted to one side or the other. The whole saddle may be tilted forward or back by turning the support E in the head B' of the saddle-post and adjusting it, as previously described.

The steering-post D has lines of transverse corrugations upon opposite sides in the line of the direction of travel of the machine. If it is desired to change the position of the steering-post in order to allow the handle-bar to be reversed, the clamp G, which locks the post in the socket C, may be lifted out and turned entirely around, reversing its position and bringing the line of corrugations which were in front to the rear, the rear ones being moved to the front. The interior of the steering-post socket has a guide formed along the front, which serves to engage with either of the projecting corrugated faces of the steering-post, while the other face is engaged and locked by the cam-block, as previously described. These two guides serve to maintain a post absolutely in its proper line and to prevent its being twisted out of place.

In order to regulate the position of the cam-lever and maintain it at the rear of the post whenever the latter has been turned around, the lever itself is mounted upon a sleeve U, which is turnable upon the exterior of the socket C, turning between proper guiding ribs or flanges, and when either of the lines of corrugations of the post are brought into line the cam-block H, which is actuated by the lever G, enters through a slot in the rear of the socket-tube and engages the corrugations which may be brought into line with the slot.

It will be seen that by this construction the machine may be practically so dismantled as to render it impossible for a thief to steal and ride it away, as it is only necessary to turn the cam and unlock the handle-bar post, which may then be withdrawn and carried off, leaving the machine in such a condition that it cannot be ridden away. The adjustment is also of value, because it allows the handle-bars to be turned instantly, so as to stand in line with the frame and wheels, and thus enables the machine to pass through narrow doorways or openings. It also makes it easy to pack for shipments and in many ways to handle it more readily than where all the parts are rigidly secured together.

The cam-heads G² have holes at g for the fulcrum-pins, about which they turn, and

curved slots g^2 , through which the pins pass to connect the cams with the plates or blocks H. Both the ends and the sides of the cams are slightly flattened, so that they press 5 squarely against the adjacent face of the plate H when the lever G is turned to release the pressure or to apply it to lock the parts, and this prevents any accidental loosening of the cam from either position.

10 Having thus described my invention, what I claim as new, and desire to secure by Letters Patent, is—

15 1. The combination with a bicycle, of a seat-post having a head slotted vertically in the line of travel of the machine, radial interlocking corrugations formed on the inner faces of the head, a seat-supporting bar having a correspondingly-corrugated circular head adapted to fit between the sides of the seat-post 20 head, a shaft extending through the seat-post head and the corresponding part of the seat-supporting bar, a cam-lever fulcrumed to the end of the shaft and adapted to close and lock the corrugated meeting faces, said shaft having 25 its opposite end threaded, and a nut on said threaded end for adjusting the shaft with relation to the lever.

30 2. The combination with a seat-post having a head split or slotted downward from the upper end, the sides of which are capable of moving to and from each other, of a seat-supporting bar having a circular projection fitting between the sides of the seat-post head and correspondingly corrugated so as to engage 35 the corrugations on the inner faces of said head, a shaft passing centrally through the head and the interior disk, said shaft having one end screw-threaded and adapted to receive a nut and washer whereby the adjustment of the parts is effected, and a cam 40 fulcrumed in the opposite end adapted to close the parts of the seat-post head and clamp them against the corrugated disk of the seat-support, substantially as described.

45 3. In a bicycle, a seat-post, a seat-supporting bar with means for adjustably clamping it in the top of the seat-post, said bar having corrugations upon the surface and channels or grooves upon each side parallel with the 50 upper surface, a block fitting and slidale

within said grooves or channels and having a cam-lever fulcrumed in the upper part thereof, a cam-block having a face corrugated to engage with the face of the supporting-bar and loosely connected with the cam-lever so 55 that by the movement of the cam-lever the block is locked in engagement with the supporting-bar.

4. In a bicycle, a seat-post and a seat-supporting bar fitted thereto, a saddle-block slideable longitudinally upon the seat-supporting bar, the seat-springs, a cam-block with interlocking face whereby said block may be engaged with and locked upon the supporting-bar, said block having holes made through its 65 opposite sides for the reception of the seat-springs, and cam-levers fulcrumed transversely and adapted to engage and lock said seat-springs at any desired point.

5. In a bicycle, the combination of a post, 70 a two-part elastic head formed of separated disks with corrugated interior faces, a corresponding corrugated disk fitting between said first-named disks, and a cam and connection permitting the first-named disks to expand 75 and the intermediate disk to be adjusted, said cam and connection locking the disks after the adjustment is obtained.

6. The combination with the movable post and a socket-post of a bicycle, of a cam having 80 a slotted head and an actuating-lever integral therewith, and fulcrumed on the socket-post, a cam-block having a pin loosely engaging with the slotted head of the cam and having teeth or corrugations adapted to engage 85 the toothed or corrugated surface of the post, said head of the cam being flattened on one side whereby the turning of the lever in one direction will disengage the block from the post and the turning of the lever in the opposite direction will lock the post to its socket 90 and also lock the lever against accidental movement.

In witness whereof I have hereunto set my hand.

EDWARD H. CHAPPUIS.
